Patented May 25, 1915.

UNITED STATES PATENT OFFICE.

PAUL T. ROEDER, OF BLOOMINGTON, ILLINOIS.

AUTOMATIC CATCH.

1,140,852.

Specification of Letters Patent. Patented May 25, 1915.

Application filed January 21, 1915. Serial No. 3,455.

To all whom it may concern:

Be it known that I, PAUL T. ROEDER, a citizen of the United States, and a resident of Bloomington, in the county of McLean and State of Illinois, have invented certain new and useful Improvements in Automatic Catches, of which the following is a full, clear, and exact specification.

My invention is concerned with automatic catches, preferably adjustable, for holding swinging members, such, for instance, as cellar windows, in any desired position, which catch acts automatically to lock the window in any position, and which can be released by a simple movement of the window, or other member to which it is applied, from its locked position.

To illustrate my invention, I annex here-to a sheet of drawings, in which the same reference characters are used to designate identical points in all the figures, of which—

Figure 1 is a side elevation of a cellar-window casing and sash having my invention applied thereto; Fig. 2 is a front elevation of the same; Fig. 3 is a detail on an enlarged scale, illustrating the relationship of the locking parts; and Fig. 4 is a similar view, illustrating the same in another position.

To illustrate my invention in its use for which it is primarily designed, I have shown a casing *a* for a cellar-window, having a sash *b* hinged therein at its upper edge by the hinges *c*. These elements, of course, operate in the customary manner.

The locking mechanism comprising my invention, which is applied to the swinging sash *b*, but which might be applied to any other similarly located movable member, consists of the catch-pin *d*, which is secured to the sash in any desired manner, as by screws passed through the flattened shank *e* thereof and into the sash. Coöoperating with this locking pin is the locking bar *f*, which is loosely pivoted between the ears *g* of the bracket *h*, which is secured to the casing in any desired manner, as by the screws shown. This locking bar *f* is provided with one or more locking recesses *j*, which preferably have the shape shown, and which necessarily have the inclined edge *k* for the purpose to be described. Of course I may employ simply the single locking-recess, where the window is to be held in only one position, but I preferably employ the plu-

rality shown, so that the window can be adjusted in any one of several positions. Associated with each of the locking recesses *j* is the dog *l*, which is loosely pivoted on the bar by the bearing pin *m*, which may be secured in place in any desired manner, preferably by riveting. It is necessary for efficient operation that these dogs be pivoted rather loosely so that their position will always be controlled by gravity, subject to the limiting action of the abutments hereinafter described. The essential feature of these dogs is their location relative to the locking recess and the bearing surface *n* formed on the lower edge thereof and operating in the manner to be described. To limit the movement of the dogs *l* and to insure their being in the proper position for the action to be subsequently described, I employ in connection with each dog the abutment *o*, which preferably takes the form of a lug cast integral with and projecting from the side of the bar adjacent the edge of the locking recess *j*. I preferably also employ the similar abutment *p*, located on the opposite side of the bearing pin *m* and serving to prevent the dog being moved out of operative position at the other extreme of its possible movement.

With these elements, the operation of the device is as follows: Supposing that the window-sash is closed, and it is desired to open the same, the user merely grasps the handle *q*, secured preferably at the center of the lower edge of the sash, and swings it out. As the pin *d* reaches each locking recess *j*, it engages the side *r* of the dog *l* and swings it out of the way so that it can enter the recess *j*. If the window is to be stopped so as to be held open by the first dog encountered, the movement of the window is stopped any time after the pin passes the edge of the recess next to the abutment *o* and before the pin passes the position of the parts shown in Fig. 3. Releasing the sash in this position causes it to start to swing back, and in swinging back the pin *d* enters the recess *j* and is held thereby from closing, and the harder the sash presses against the bar, the more tightly it is locked from further movement. When the sash is to be opened, all that is necessary is for the handle *q* to be grasped and the sash lifted open a little farther until the pin *d* passes the position shown in Fig. 3, after which it is held in the open position by the second dog encountered.

which the dog *l* that it has just passed immediately swings by gravity into the position in which the dog stands substantially vertical, and if the sash is now released and allowed to fall by gravity, or is shoved to its closed position, the pin *d*, as it reaches each locking recess, contacts with the side *n* of the locking dog associated with that recess, and by its continued engagement with that side, as indicated by the position of the parts in Fig. 4, holds the dog over the locking recess until the pin has passed said locking recess, and this action of the pin in passing all the dogs insures the sash being closed completely without any trouble whatever. At the outer end of the locking bar *f*, I may place the notch *s*, which catches the pin *d* before the sash can be swung open far enough to disengage the locking bar from the pin.

With the construction shown, it will be seen that I have devised a simple and automatically-operated catch that enables me to move the sash *b*, or any similar member to which it is applied, to any desired position and lock the same in that position, and unlock and close it, without any direct manipulation whatever of the locking devices.

While I have shown and described my invention as embodied in the form which I at present consider best adapted to carry out its purposes, it will be understood that it is capable of modifications, and that I do not desire to be limited in the interpretation of the following claims except as may be necessitated by the state of the prior art. What I claim as new, and desire to secure by Letters Patent of the United States, is:

1. In a device of the class described, the combination with a movable member adjustable to different positions and carrying a catch pin, of a bar having a locking recess adapted to coöperate with the pin to hold the member with its pin in the locking recess and thus held adjusted away from its normal position, and means coöperating with the pin and bar and preventing the engagement of the pin with the recess during the return movement of said member, which means is brought into action by simply moving the member on to disengage the pin from the recess.

2. In a device of the class described, the combination with a movable member adjustable to different positions and carrying a catch pin, of a bar having a locking recess adapted to coöperate with the pin to hold the member with its pin in the locking recess and thus held adjusted away from its normal position, and means coöperating with the pin and bar and allowing the pin to enter the recess to lock the member when it is stopped with the pin opposite the recess, but preventing the pin from entering

the recess to lock the member as it is moved freely past the recess in either direction provided no stop is made opposite the recess.

3. In a device of the class described, the combination with a movable member adjustable to different positions and carrying a catch-pin, of a bar having a locking recess adapted to coöperate with the pin to hold the member with its pin in the locking recess and thus adjusted away from its normal position, and a dog pivoted to the bar adjacent the recess and serving to prevent the pin entering the recess during the return movement of the member. 70

4. In a device of the class described, the combination with a movable member adjustable to different positions and carrying a catch-pin, of a bar having a locking recess adapted to coöperate with the pin to hold the member with its pin in the locking recess and thus adjusted away from its normal position, a dog pivoted to the bar adjacent the recess and serving to prevent the pin entering the recess during the return movement of the member, and an abutment to limit the movement of the dog, for the purpose described. 80

5. In a device of the class described, the combination with a movable member adjustable to different positions and carrying a catch-pin, of a bar having a locking recess adapted to coöperate with the pin to hold the member with its pin in the locking recess and thus adjusted away from its normal position, a dog pivoted to the bar adjacent the recess and serving to prevent the pin entering the recess during the return movement of the member, and a pair of abutments to limit the movement of the dog, for the purpose described. 90

6. In a device of the class described, the combination with a movable member adjustable to different positions and carrying a catch-pin, of a bar having a locking recess adapted to coöperate with the pin to hold the member with its pin in the locking recess and thus adjusted away from its normal position, a dog pivoted to the bar adjacent the recess and serving to prevent the pin entering the recess during the return movement of the member, and a pair of lugs extending from the bar into the plane of the dog to coöperate therewith and prevent its swinging beyond its operative position. 100

7. In a device of the class described, the combination with a member hinged at one edge thereof adjustable to different positions and having a pin connected thereto traveling through the arc of a circle as said member is swung on its hinge, of a bar pivoted on the stationary support to which the member is hinged and having a locking recess adapted to coöperate with the pin to hold the member adjusted away from its normal position, and means coöperating with the 110

pin and bar and allowing the pin to enter the recess to lock the member when it is stopped with the pin opposite the recess, but preventing the pin from entering the recess to lock the member as it is moved past the recess in either direction provided no stop is made opposite the recess.

8. In a device of the class described, the combination with a member hinged at one edge thereof adjustable to different positions and having a pin connected thereto traveling through the arc of a circle as said member is swung on its hinge, of a bar pivoted on the stationary support to which the member is hinged and having a locking recess adapted to coöperate with the pin to hold the member adjusted away from its normal position, and a dog pivoted to the bar adjacent the recess and serving to prevent the pin from entering the recess during the return movement of the member.

9. In a device of the class described, the combination with a member hinged at one edge thereof adjustable to different positions and having a pin connected thereto traveling through the arc of a circle as said member is swung on its hinge, of a bar pivoted on the stationary support to which the member is hinged and having a locking recess adapted to coöperate with the pin to

hold the member adjusted away from its normal position, a dog pivoted to the bar adjacent the recess and serving to prevent the pin from entering the recess during the return movement of the member, and an abutment to limit the movement of the dog, for the purpose described. 35

10. In a device of the class described, the combination with a member hinged at one edge thereof adjustable to different positions 40 and having a pin connected thereto traveling through the arc of a circle as said member is swung on its hinge, of a bar pivoted on the stationary support to which the member is hinged and having a locking recess adapted 45 to coöperate with the pin to hold the member adjusted away from its normal position, a dog pivoted to the bar adjacent the recess and serving to prevent the pin from entering the recess during the return movement of the member, and a pair of abutments to limit the movement of the dog, for the purpose described. 50

In witness whereof, I have hereunto set my hand and affixed my seal, this 12th day 55 of January, A. D. 1915.

PAUL T. ROEDER. [L. S.]
